(57) **CLAIM**

The ornamental design for a wire clip and cover assembly, as shown and described.

DESCRIPTION

FIG. 1 is a perspective view of the wire clip of a wire clip and cover assembly, shown separated from the wire clip and cover assembly, in accordance with the present design;

FIG. 2 is a front side view of the wire clip of FIG. 1;

FIG. 3 is a rear side view of the wire clip of FIG. 1;

FIG. 4 is a left side view of the wire clip of FIG. 1;

FIG. 5 is a right side view of the wire clip of FIG. 1;

FIG. 6 is a top side view of the wire clip of FIG. 1;

FIG. 7 is a bottom side view of the wire clip of FIG. 1;

FIG. 8 is a perspective view of a right side cover, shown separated from the wire clip and cover assembly, with the left side cover being identical to the right side cover, in accordance with the present design;

FIG. 9 is a front side view of the right side cover of FIG. 8;

FIG. 10 is a rear side view of the right side cover of FIG. 8;

FIG. 11 is a top side view of the right side cover of FIG. 8;

FIG. 12 is a bottom side view of the right side cover of FIG. 8;

FIG. 13 is a left side view of the right side cover of FIG. 8;

FIG. 14 is a right side view of the right side cover of FIG. 8;

FIG. 15 is a perspective view of the wire clip and cover assembly, shown in an environment of use;

FIG. 16 is a front side view of FIG. 15;

FIG. 17 is a rear side view of FIG. 15; and,

FIG. 18 is a perspective view of the wire clip and cover assembly, shown reduced in scale and in another environment of use.

The broken lines shown on the wire clip depict portions of the wire clip that form no part of the claim. The broken lines shown in FIGS. 15-18 depicting environments of use form no part of the claim.

The wire clip and cover assembly includes identical right side and left side covers. Because both covers are identical, the left side cover is not shown. FIGS. 1-7 depict wire clip alone, disassembled from the right and left side covers. FIGS. 8-12 depict the right side cover, disassembled from wire clip and the left side cover. The broken lines shown in FIGS. 15-18 depict the environment in which the wire clip and cover assembly is used and are included for environmental purposes only.
